ROBERT PRINGLE, OF LONDON, ENGLAND.

GAS-STOVE FOR COOKING PURPOSES, &c.

SPECIFICATION forming part of Letters Patent No. 605,011, dated May 31, 1898.

Application filed August 28, 1897. Serial No. 649,864. (No model.)

To all whom it may concern:

Be it known that I, ROBERT PRINGLE, of 11 Eliot Park, Blackheath, London, in the county of Kent, England, have invented new and useful Improvements in Gas-Stoves for Cooking and other Purposes, of which the following is a full, clear, and exact description.

This invention relates to a gas-heated stove adapted to roasting, baking, and other cooking purposes.

The invention will be described with reference to the accompanying drawings, wherein—

Figures 1 and 2 are elevations in vertical section on planes at right angles to one another. Fig. 3 is a horizontal section of the lower part of the stove. Fig. 4 is a top plan showing removable burners for boiling purposes.

The stove comprises an outer casing A, of rectangular or other form, which may be made of enameled cast or sheet iron lagged with a non-conducting material. It contains roasting-spaces B B', and above these a hot-chamber C, which may serve as an oven and from which the upper one, B', of the two roasting-spaces is separated by a horizontal partition D. Access may be had to the spaces B B' and the chamber C by doors E and F, Fig. 2, which are also lagged with non-conducting material and provided with tale windows e and f and with brackets supporting thermometers e', which are visible through the windows.

Within the casing A, along the sides and back of the lower roasting-chamber B, is an air-heating chamber H, inclosed in a sheet-metal casing offset within the casing A, and in the top and bottom plates h h' of this chamber A are fixed rows of vertical heat-radiating flues G, preferably of fire-clay, which tubes traverse the air-heating chamber H and open at top and bottom to the upper and lower roasting-spaces B and B'. In the lower part of the roasting-chamber B and beneath the bottom plate h' of the air-heating chamber H are burners i upon a gas-pipe I, which connects with a regenerative gas-heating tube J, connected with the gas-supply below and passing up through chamber H and down through one of the flues G to the pipe I. Air is admitted to the chamber H through

apertures h² at the bottom or lower part of the casing A and is caused by a baffle h³ to pass up and circulate in the downward direction around the flues G, between the baffle h³ and the inner wall h⁴ of the chamber H, whereby the air becomes heated before passing down between the baffle h³ and another baffle h⁵, which extends downward to a point below the level of the burners, so that the air entering the lower part of the roasting-space B in proximity to but below the level of the burners will not blow the flames inward toward the roasting-space or disturb the steadiness of the flames.

As above mentioned, the flames are not directly beneath the flues G, and in order to conduct the hot gases toward the flues and prevent them spreading directly into the roasting-space B the inner wall h⁴ of the chamber H is prolonged downward below the bottom of the said chamber, so as to form a curtain, which also screens the burners from fat falling through the space B. The roasting-space B is divided from the upper roasting-space B' by one or more horizontal gratings K, upon which a joint of meat or a cooking utensil may be placed, the grating or gratings being removable to admit of a joint of meat being hung in the conjoined spaces B and B', as indicated in dotted lines in Fig. 2. The area of the grating may correspond to that of the space surrounded by the air-heating chamber, or it may extend over the flues G, as shown. In any case the burners should not be directly beneath the flues G, but at one side thereof, more or less, beneath the intermediate portions of the bottom plate h' of the air-heating chamber H, as shown, so as to avoid all liability of fat or liquid falling through the flues G onto the burners. The hot air and gases pass from the upper roasting-space B' through holes l in the bottom plate D of the oven C, the draft and ventilation being regulated by a hit-and-miss damper L, while a baffle or baffles, such as L', may be so fixed as to direct the course of the hot air and gases on leaving the apertures l in such a way as to distribute the hot air and gases equally through the oven. The effect of the holes l beneath the floor of the oven and entirely to one side thereof and partially screened by the baffle L' is that articles

placed in the oven are out of line of the draft and therefore out of contact with vapors from the roasting-spaces.

The top plate *c* of the oven-chamber *C* is provided with apertures *M* for the escape of the heated air and products of combustion, the heated air being utilized for effecting the complete combustion of gas-jets at ring-burners *N* to be used for heating vessels placed over the said burners *N*. These burners are supplied with heated gas from the gas-heater *J* through pipes *j*, which pass up inside the stove, so as to maintain or still further increase the heat of the gas, the pipes *j* passing out through the side of the casing at the upper part, where they are provided with stop-cocks *j'* to control the supply of gas to the ring-burners *N*, and with supporting-sockets in which the arms carrying the ring-burners *N* are pivoted, so that they may be swung entirely aside when not required. The burners *N* are surrounded by circular casings or kettle-supports *n*, upon which the vessels are placed and which are removable to admit of swinging the burners entirely aside, so as to leave the whole top surface of the oven *C* unencumbered and available as a hot-plate. When the burners are swung aside for that purpose, the stove would be surmounted by a removable grating *O*, provided with upstanding sides *O'* to prevent articles placed thereon from falling off. The space thus inclosed may be made to form a removable oven, if required, by inclosing the top by a cover and providing a door in the front side.

The bottom of the roasting-chamber *B* is apertured at the center and closed by a basting-dish *P*, supported and fitted to slide in guides, so as to admit of easy removal and prevent the access of cold air to the burners.

It will be observed that a joint placed in the lower part of the roasting-space *B* will be cooked only by radiant heat from the flames, flues, and sides of the chamber without exposure to any fumes or gaseous products of combustion, while the upper roasting-space *B'* extends to the full area of the casing *A* and is traversed by the hot air and products of combustion from the flues.

Having now particularly described and ascertained the nature of the said invention and in what manner the same is to be performed, I declare that what I claim is—

1. A gas-heated cooking-stove having a casing comprising a roasting-space, a door at the front of the roasting-space, an air admission and heating chamber surrounding the remaining sides of the roasting-space and located at the lower part thereof, the upper part of the air-heating chamber being offset or inwardly projecting and being traversed by vertical flues leading from the space beneath to the roasting-space above, burners in the space beneath the air-heating chamber but not directly beneath the flues, air-inlets outside of

a baffle rising within the chamber and directing the incoming air against the flues, and a depending baffle or curtain inclosing a downcast passage opening to the combustion-chamber at or below the level of the burners therein, substantially as specified. 70

2. A gas-heated cooking-stove having a casing, comprising a roasting-space, a door at the front of the roasting-space an air admission and heating chamber surrounding the remaining sides of the roasting-space and located at the lower part thereof, the upper part of the air-heating chamber being offset or inwardly projecting and being traversed by vertical flues leading from the space beneath to the roasting-space above, burners in the space beneath the air-heating chamber but not directly beneath the flues, air-inlets outside of a baffle rising within the chamber and directing the incoming air against the flues, and a depending baffle or curtain inclosing a downcast passage opening to the combustion-chamber at or below the level of the burners therein, and an inner curtain depending within the line of the burners so as to separate the upper part of the combustion-space from the inclosed roasting-space to such an extent as to prevent the flames being deflected inward and the products of combustion from passing up through the roasting-chamber, while permitting direct radiation of the heat from the flames to the roasting-space, substantially as specified. 80 90

3. A gas-heated cooking-stove having a casing, comprising a roasting-space having a door at the front of the roasting-space, an air admission and heating chamber surrounding the remaining sides of the roasting-space and located at the lower part thereof, the upper part of the air-heating chamber being offset or inwardly projecting and being traversed by vertical flues leading from the space beneath to the roasting-space above, burners in the space beneath the air-heating chamber but not directly beneath the flues, air-inlets outside of a baffle rising within the chamber and directing the incoming air against the flues, and a depending baffle or curtain inclosing a downcast passage opening to the combustion-chamber at or below the level of the burners therein, an inner curtain depending within the line of the burners so as to insure the passage of the products of combustion through the flues alone while permitting of direct radiation from the flames to the roasting-space, and a grating dividing the roasting-space into a lower space heated only by radiation and an upper space heated mainly by convection-currents from the flues discharging therein, substantially as specified. 105 110 115 120
